United States Patent Office

Des. 233,809
Patented Dec. 3, 1974

233,809

CHAIR

Warren Platner, New Haven, Conn., assignor to
Steelcase Inc., Grand Rapids, Mich.

Filed Mar. 26, 1973, Ser. No. 344,850

Term of patent 14 years

Int. Cl. D6—01

U.S. Cl. D6—31

FIG. 1

FIG. 2

FIG. 3

FIG. 4

FIG. 5

FIG. 6

FIG. 7

FIG. 8.

FIG. 9

FIG. 10

FIG. 15.

FIG. 1 is a front elevational view of the chair; embodying my design;

FIG. 2 is a side elevational view of the chair;

FIG. 3 is a rear elevational view of the chair;

FIG. 4 is a top plan view of the chair;

FIG. 5 is a bottom plan view of the chair;

FIG. 6 is a generally front perspective view of the chair;

FIG. 7 is a generally rear perspective view of the chair;

FIG. 8 is a cross-sectional view taken along plane VIII—VIII of FIG. 6;

FIG. 9 is a cross-sectional view taken along plane IX—IX of FIG. 6;

FIG. 10 is a cross-sectional view taken along plane X—X of FIG. 6;

FIG. 11 is a generally front perspective view of a chair which is an alternative embodiment of my design;

FIG. 12 is a cross-sectional view taken along plane XII—XII of FIG. 11;

FIG. 13 is a cross-sectional view taken along plane XIII—XIII of FIG. 11;

FIG. 14 is a cross-sectional view taken along plane XIV—XIV of FIG. 11; and

FIG. 15 is a front elevational view of yet another alternative embodiment of my design.

I claim:

The ornamental design for chair, substantially as shown.
